UNITED STATES PATENT OFFICE

RUDOLF BUNGEROTH, OF DUSSELDORF, GERMANY

TUBE EXPANDER

Original application filed July 23, 1927, Serial No. 208,013, and in Germany December 29, 1925. Divided and this application filed December 17, 1927. Serial No. 240,884.

The invention relates to apparatus for expanding metal tubes with regular or varying thickness of wall, and is a division of my co-pending application Serial No. 208,013, filed

5 July 23rd, 1927, now Patent 1,682,724.

The expanding of tubes by inclined roller devices by the use of a mandrel has been several times attempted. The arrangements hitherto preferably used, in which the mandrel-shafts are subjected to pressure, have given rise to considerable difficulty since the mandrel, subjected to pressure, yields more or less in accordance with the degree of the rolling pressure and accordingly alters its position relative to the rollers.

15 The result is an irregular and uncommercial manufacture.

It has also been proposed to secure the mandrel to a shaft placed at the inlet side 20 of the machine whereby pressure on the mandrel or the mandrel shaft is avoided.

However, in these machines also it is not possible to realize the main condition for the production of a uniform product, which consists in maintaining the mandrel during the 25 working period exactly in its position between the rollers.

These defects of the known arrangements have been particularly noticeable in the manufacture of tubes of considerable length, as 30 they are now generally required.

The present invention relates to machines in which the expanding is effected by means of a mandrel which is secured to a mandrel shaft placed on the inlet side of the machine and it is differentiated from the known apparatus in that the mandrel shaft is adjustably arranged.

35 In this manner, it is possible to maintain the mandrel always in a definite position between the rollers during the working period, and consequently to compensate for any alteration of the mandrel shaft.

40 The adjusting means may be of any suitable kind.

A coarse or fine adjustment of the mandrel may be provided. In the improved machine, the expanding of tubes of considerable length 45 and constant dimensions presents no difficult-

ties as the mandrel always maintains its definite position between the rollers.

The invention is illustrated by the accompanying drawings in which—

Figure 1 is a longitudinal section showing 55 one form of the invention;

Fig. 2 is a longitudinal section showing another form of the invention.

It has already been proposed to effect movement of a mandrel by means of an hydraulic piston in rolling operations in which the mandrel and article which is being rolled are moved to correspond with the rolling operation. In the present case it is not a question of moving the mandrel and tube corresponding to the rolling operation, but rather one of giving an absolutely definite position to the mandrel relative to the rollers and retaining the mandrel in this position during the working period.

70 Two constructions embodying the invention are illustrated in the drawings.

Figure 1 shows a disc apparatus in plan view in which roller discs *a*, which are relatively disposed in known manner, act in conjunction with the mandrel *b* to effect the expansion of the tube. The mandrel shaft *c* is in this case arranged on the entry side of the apparatus. To one end of the mandrel shaft is secured the mandrel *b*, the other end being connected to an adjusting device which consists of a piston rod 3, piston 4 and cylinder 5. With this construction the mandrel shaft is not subjected to a bending, but to a tensile stress. In this manner even in 75 the case of considerable lengths, which exceed that of the tube to be produced by from about one to two meters, a considerable reduction in the cross sectional area of the mandrel shaft is effected, in contrast to the mandrel shafts heretofore used which have been subjected to pressure, and, therefore, made very heavy with resulting inconvenience in handling. The mandrel shaft which is subjected to tension, does not alter its length 80 in proportion to the roller pressure, and, therefore, retains the mandrel in the adjusted position under varying pressure.

85 In the construction illustrated in Figure 1 the mandrel shaft *c* is connected to one end 89

of the piston rod 3. The other end of the piston rod 3 is connected with the piston 4, which moves in the cylinder 5 in known manner. Pipes 6 and 7 are provided at the ends of the cylinder 5 through which pressure may be transmitted to the cylinder by means of a fluid, which may be liquid or gaseous. Suitable known controls may be provided whereby the fluid pressure on both sides of the piston may be accurately regulated and an absolutely definite position thereby given the mandrel. It is evident that the mandrel position may be maintained by the means just described or that if the mandrel shaft 15 should have altered its length because of heat during the rolling, the position of the mandrel may be readjusted during the rolling.

If a particularly fine adjustment of the mandrel is required a supplementary fine 20 adjustment means may be provided.

Fig. 2 illustrates fluid actuated means for giving the mandrel coarse adjustment, to which is added other means for giving fine adjustment. In this case a screw spindle, 25 worm wheel, worm, and hand-wheel are illustrated as giving the fine adjustment.

An arrangement is here shown which is somewhat similar to that illustrated in Figure 1. A mandrel *b* is fastened to one end of a mandrel shaft *c* which is arranged on the entry side of the apparatus. The other end of the mandrel shaft, as in Figure 1, is connected to an adjusting device which consists primarily of a piston rod 3¹, piston 4 and cylinder 5.

Instead of attaching the mandrel shaft directly to the piston rod as is the case in the example illustrated in Figure 1, in the present case the mandrel shaft is connected to one 40 end of a stem 8 whose other end 9 is expanded and threaded. The threaded end 9 of the stem 8 turns within a flanged nut 10, with whose internal threads it engages.

The piston rod 3¹ is extended beyond the 45 piston 4 away from the mandrel and contains a bore into which the nut 10 extends and in which the nut is free to rotate. The nut 10 has a flange 11 which bears on one side against a shoulder 12 formed on the piston rod 3¹, and on the other side against a plate 13 spaced from the shoulder 12. Thus, while the nut 50 is free to rotate in the bore of the piston rod it is constrained against axial movement with respect to the piston rod.

55 As here shown, a worm wheel 14 is attached to the flanged nut 10 and serves to rotate it. A worm 15, upon whose shaft 16 is a hand-wheel 17, provides means for operating the worm wheel and with it the nut 10. Thus the 60 threaded end 9 of the stem 8 is moved longitudinally of the piston rod and piston, and the mandrel is given fine adjustment.

The cylinder may be arranged pivotally to facilitate connecting and disconnecting the 65 piston rod and mandrel shaft.

By means of the present invention it is therefore possible to maintain the mandrel always in a definite position between the rollers during the working period, and also to adjust the mandrel's position during the 70 working period to compensate for any alteration in the length of the mandrel shaft.

I claim:

1. In apparatus for expanding metal tubes, a mandrel shaft located at the inlet 75 side of the apparatus, and a mandrel carried by said shaft, in combination with fluid actuated means for giving rough adjustment to said mandrel during rolling, and other means axially movable with said fluid actuated means and mandrel shaft for giving fine adjustment to said mandrel.

2. In apparatus for expanding metal tubes, a mandrel shaft located at the inlet side of the apparatus, and a mandrel carried 85 by said shaft, in combination with fluid actuated means for giving rough adjustment to said mandrel during rolling, and screw means axially movable with said fluid actuated means and mandrel shaft for giving fine 90 adjustment to said mandrel.

3. In apparatus for expanding metal tubes, a fluid cylinder mounted at the inlet side of the apparatus, a piston reciprocable 95 therein, a mandrel shaft, a mandrel carried by the mandrel shaft, means connecting said piston and mandrel shaft, and means for regulating fluid pressure in the cylinder on both sides of the piston to position the mandrel and to maintain the mandrel in adjusted positions during expansion of the tube. 100

4. In apparatus for expanding metal tubes, a fluid cylinder mounted at the inlet side of the apparatus, a piston reciprocable 105 therein, a mandrel shaft, a mandrel carried by the mandrel shaft, means connecting said piston and mandrel shaft, and means for regulating fluid pressure in the cylinder on both sides of the piston for giving rough adjustment to said mandrel, and other means 110 associated with the piston and mandrel shaft for giving fine adjustment to the mandrel.

In testimony whereof I have signed my name to this specification. 115
